UNITED STATES PATENT OFFICE

1,992,264

VEHICLE-WHEEL ALIGNMENT INDICATOR

Ira A. Weaver, Springfield, Ill., assignor to Weaver Manufacturing Company, Springfield, Ill., a corporation of Illinois

Application March 30, 1931, Serial No. 526,385

1 Claim. (Cl. 33—203)

My invention pertains to certain structural betterments, with resulting functional advantages, in appliances for indicating the alignment of vehicle-wheels, whereby their condition, as to in or out toe may be ascertained with facility, rapidity, and accuracy.

One object of the invention is the provision of an apparatus of this kind which is so constructed that it is capable of withstanding the passage over it of the heaviest type of motor-vehicles while their wheels are undergoing test.

Another feature of the invention resides in the improved and novel means for producing the sidewise motion of the traction-plate with which the vehicle-wheel contacts, and a similar motion for the rollers of the roller-bearings which carry or support such plate.

A further characteristic of the new construction is the means for securing such cover or traction-plate in place.

An added purpose of the invention is to provide a construction of this character in which the pointer or index moves in the direction in which the wheel is out of line.

Still a supplemental aim of the invention is to supply an appliance of this general style in which the cover or traction-plate is locked against movement by friction until the vehicle-wheel has its weight properly imposed on the bearings which support the plate.

In the accompanying drawings, which form a part of this specification and to which reference should be had, a present, preferred embodiment of the invention has been illustrated in detail, and, for simplicity, like reference numerals have been employed to designate the same structural parts throughout the several views.

In these drawings:—

40 Figure 1 is a plan view of the vehicle-wheel alignment indicator;

Figures 2, 3, and 4 are enlarged cross-sections through the appliance on lines 2—2, 3—3, and 4—4, respectively, of Figure 1;

45 Figure 5 is a plan view of the base portion of the structure with the top or cover-plate removed; and

Figure 6 is a view of the underside of the cover or traction-plate.

50 Referring to these drawings, it will be perceived that the apparatus includes a flat, metal base-plate 11 adapted to rest on the floor or ground and equipped with a carrying-handle 12 along the middle portion of one of its sides by means of which the whole appliance may be readily carried about, whereby the apparatus may be properly characterized as easily portable.

Secured to the top face of such base-plate 11 are a plurality of parallel, transverse, flat track-bars 13, 13, conveniently or desirably

fastened or secured in place by rivets 14, 14 or in any other suitable manner.

In the present instance, four long anti-friction rollers 15, 15 bear and roll on such cross-tracks 13, 13, and the two ends of such rollers are maintained properly spaced apart by two end-bars 16, 16 in which such rollers have bearings.

A lever 17 is fulcrumed at its center on the base-plate 11 on an upstanding stud 18, and a corresponding lever 19 of equal length is similarly rockingly mounted midway its length on the baseplate by means of a stud 20.

One end of lever 19 is longitudinally slotted at 21 to rockingly receive an adjacent, rounded end 22 of the other lever 17, the part 22 snugly or accurately fitting in the slot, whereby when one lever is rocked or turned on its fulcrum, the associated or companion lever will rock in like manner and in equal degree.

A metal plate 23, positioned crosswise the structure, bears on the upper surface of the base-plate and is adapted to slide thereon, its central part 24 being elevated to extend over the lever 19 to which it is pivoted at its middle at 25, and the other or lower portions of the bar 23 have pairs of upstanding lugs 26, 26 on opposite sides of and in contact with the four bearing-rollers 15, 15.

Thus, as lever 19 rocks, the set or group of rollers is correspondingly shifted laterally of the appliance by reason of the mechanical connection 23 between the lever and the rollers.

In like or similar manner, lever 17 has a connection 23 with the other end portions of the rollers.

Metal loops 27 fastened to the base-plate and through which the two levers extend, as is clearly shown, constitute stops for limiting or restricting the extent of rocking or swinging movement 40 of the two levers.

Near one end of the base-plate 11, a bracket 28 is secured by screws or rivets 29, and, inasmuch as the lower edge portion of the adjacent bar 16 slides crosswise the apparatus between the edge 45 of the neighboring track-plate 13 and the bracket 28, the rollers and their cage construction cannot shift or move lengthwise the appliance.

The outer end of lever 17 is slotted at 30 to accommodate or receive the rounded end 31 of an index of pointer 32, the outer end of which cooperates with a scale 33 on a plate 34 secured to the base-plate, beyond the end of the cover-plate described below, such scale being desirably graduated in feet per mile.

From an understanding of the construction so far as now described, it will be obvious that the pointer will move over the scale an amount proportional to the extent of the lateral travel of the rollers and their associated cage construc- 60

tion, and in a direction opposite to the movement of such rollers.

The companion traction or cover plate 35, which has a downturned flange around its margin, has cross track bars or plates 36, 36 fastened to its underside, and these bear or rest on the tops of the several rollers 15 directly above the lower track-bars 13, so that the weight imposed on such top plate by the vehicle-wheel undergoing test is transmitted directly to such track bars and the intervening rollers of the anti-friction construction, whereby the cover-plate can readily shift sidewise if the wheel is out of line.

Cover-plate 35 has two depending, threaded studs 37, 37, one of which occupies slot 30 and the other of which is in a similar slot 38 in the outer end of lever 19, whereby any sidewise movement of such plate is transmitted through the studs 37 to the two connected levers, and these in turn shift the rollers and their cage sidewise an amount one-half of the cross travel of the plate, the connections 25 of the members 23 being located half way between the outer ends of the levers and their fulcrums.

Thus a proper and positive movement is imparted to the rollers through their cage construction assuring that all positions of each roller are parallel to one another, and the extent of such transverse travel of the cover-plate will be indicated by the pointer on the scale, the index end of the pointer traveling over the scale in a direction opposite to that of the movement of the traction-plate.

Owing to the specified connections of the cover-plate with the two levers and the rocking union of the adjacent ends of the levers with one another, the structure represents a mechanism which requires the cover-plate to move bodily and equally throughout its length and with all of its positions parallel to one another, thus assuring that the action of the pointer will be correct under all circumstances.

In order to hold or keep the cover or top plate appropriately in place on the device, the base-plate is equipped with a pair of brackets 39, 39 near the middle of the length of the apparatus, and the top plate has a correlated or companion pair of oppositely-facing brackets 41, 41 secured to its under surface.

When the cover-plate is in place, portions of its brackets underlie or interlock with parts of the base-plate brackets and thus prevent improper displacement of the movable, upper plate or its separation from the tester as a whole.

As is indicated in Figures 1 and 6, the front end of the top plate slopes or inclines down at 42 to facilitate the running of the wheel up onto the main portion of the plate, and, while the wheel is rolling up such incline, the plate flexes or bends downwardly sufficiently to allow the edge of its depending flange to bear on the base-plate, thus precluding side movement of the plate until the wheel is in proper and suitable position thereon.

The apparatus is operated substantially as follows:—

Assuming that the top plate is in its neutral or central position and that the pointer 32 is opposite the zero graduation of the scale, the vehicle-wheel is rolled up onto the plate lengthwise the latter and when it reaches a suitable position thereon and continues its travel thereon, the top plate will automatically shift sidewise in one direction or the other an amount corresponding to the degree of in-toe or out-toe of the wheel.

Such lateral movement of the plate is facilitated and aided by the efficiently-acting and strong, anti-friction roller-bearing which moves sidewise one-half the similar travel of the plate.

By reason of the action of the mechanism which has been fully described, the travel of the plate and of the rollers and their cage construction is maintained in perfect parallelism, thus assuring that both ends of the plate will move in equal degrees.

The index end of the pointer or hand 32 will swing in the opposite direction an amount proportional to the travel of the plate, which, of course, is in due degree to the angularity of the wheel, whereby the scale reading indicated by the pointer will show the extent of in or out toe of the wheel, and such reading will specify whether or not such deviation from the exact, straight-ahead position is proper or excessive.

It will be noted that the wheel in traveling over the full, or any certain portion of the, length of the tester covers a definite and predetermined distance, and in so doing it will force the top plate laterally or sidewise an amount corresponding to its degree of in or out toe.

Accordingly, such scale may conveniently be graduated in feet per mile or in any other desired way.

The wheel having been driven off of the plate, the reading of the pointer on the scale may be ascertained, whereupon the plate may then be replaced to its central or neutral position ready for further service.

As is indicated in the drawings, the upper surface of the top plate with which the wheel contacts is desirably made rough, preferably by slight, longitudinal elevations, so that there is no tendency for the wheel to slip sidewise on the plate while it is pushed laterally.

It will be understood that since the rollers extend substantially the full length of the movable plate, they support the latter in an anti-friction manner in a particularly effective way, so that the apparatus, even though very thin in structure, can support the heaviest type of vehicles without danger of injury to itself.

Those acquainted with this art will readily understand that the invention as presented in the appended claim is not indispensably or essentially confined to the strict structural details presented in the drawings and referred to in the specification, and that many changes or modifications may be incorporated in the construction without deviation from the fundamentals of the invention and without the forfeiture of any of its important structural or functional superior characteristics.

I claim:

In a vehicle-wheel alignment indicator, the combination of a base-plate, an elongated top plate over said base-plate and on which the vehicle-wheel to be tested is adapted to roll, and antifriction bearing means between said plates and on which said top plate is designed to travel sidewise, said top plate having an inclined end up which the vehicle-wheel is adapted to roll, said end being flexible to frictionally contact with said base-plate when said end flexes as a wheel rolls up such inclined end, the friction preventing sidewise travel of the top plate until the wheel is properly located on the plate.

IRVING A. WEAVER.
